UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

THREAD CONTROLLER FOR SEWING MACHINES.

Application filed May 23, 1924. Serial No. 715,421.

The invention relates to new and useful improvements in thread controllers for sewing machines, and more particularly a rotary thread controller for the looper threads of a 5 sewing machine.

An object of the invention is to provide a thread controller of the above type which is so constructed that if the thread breaks it cannot possibly be wound onto the rotating 10 shaft of the thread controller or the moving parts of the thread controller.

A further object of the invention is to provide a rotating thread controller which is very simple in construction, wherein the parts 15 may be readily assembled and which is readily accessible for adjustment.

These and other objects will in part be obvious and will in part be hereinafter more 20 fully disclosed.

20 In the drawings which show by way of illustration one embodiment of the invention—

25 Figure 1 is a side view with parts in section of a sewing machine embodying my improvements;

Fig. 2 is a plan view of the machine with parts broken away to show more clearly the thread controller;

Fig. 3 is an enlarged view partly in section and partly in side elevation showing the 30 thread controlling member and the parts associated therewith;

Fig. 4 is a sectional view on the line 4—4 of Fig. 3;

35 Fig. 5 is a sectional view on the line 5—5 of Fig. 3;

Fig. 6 is a detached perspective view of the 40 thread guide which directs the thread at the interior of the thread controller;

Fig. 7 is a perspective view showing the 45 thread guiding channel member and the cover plate therefor for directing the thread from the thread controller to the work supporting arm;

Fig. 8 is a view more or less diagrammatic showing the relation of the thread controller to the loopers when the loopers are at the 50 forward ends of their stroke;

Fig. 9 is a similar view but showing the 55 loopers slightly retracted;

Fig. 10 is a similar view but showing the 60 loopers at the rear ends of their stroke, and

Fig. 11 is a view partly in section and part-

ly in side elevation showing the cam for clamping the threads.

The invention is directed to a thread controller for sewing machines, and more particularly to a thread controller for a thread carrying looper. The invention is preferably embodied in a machine known as a side wheel, feed up the arm machine wherein the looper shaft extends lengthwise of the arm, and carries loopers on the outer end thereof, which move in a plane transversely of the arm as they move into and out of the needle thread loops. The looper is operated by a shaft mounted in the head of the machine and extending transversely of the looper shaft. On the end of this transverse shaft is my improved thread controller. Said thread controller preferably consists of an outer cylindrical flange mounted on a shaft and overhanging the end thereof, and a similar inner cylindrical flange. These two flanges are preferably formed integral with the supporting member and are spaced so as to form an annular groove therebetween. The lateral peripheral edges of the flanges are similarly shaped and are formed so as to provide cams for taking up and releasing the thread. Located within the inner flange is a thread guide. The threads are led from the supply through this thread guide and then across the periphery of the flanges to an outer thread guide. A nipper mechanism is provided which is adapted to engage the threads between this inner thread guide and the supply for clamping the same to prevent the controlling member from drawing off thread from the supply at intervals.

Referring more in detail to the drawings, my improved thread controller is shown as applied to a sewing machine which includes a standard 1 carrying an overhanging arm 2 in which is mounted a needle bar 3 which needle bar is reciprocated by means of a needle lever 4 mounted on the overhanging arm 2. Said needle lever 4 is reciprocated by means of an eccentric strap 5 which cooperates with an eccentric on the main shaft 6. Said needle bar 3 is provided with two needles 7, 7. The material is held on the work support by means of a presser foot 8 mounted on a presser bar 9 and held in engagement with the work support by a spring 10. The feed 100 of the machine is such as to feed the material

being stitched on to the arm. Cooperating with each needle 7, 7 beneath the work support is a thread carrying looper 11. These loopers 11, 11 are mounted on the outer end 5 of a shaft 12 which is oscillated by suitable mechanism from the shaft 6 and which is also moved endwise so that the loopers have not only a loop taking movement but also a needle avoiding movement. These parts are of the 10 usual construction and further description thereof is not thought necessary.

The looper threads are indicated at 1, 1 in the drawings. These looper threads on their way from the supply to the loopers, 15 pass first through the tension devices 13, 13 respectively, and thence through my improved thread controlling mechanism. On the end of the shaft 6 (see Fig. 4) is a cylindrical member 14 having a peripheral flange 20 15 which projects in a direction parallel with the axis of the shaft and overhangs the end thereof. The member 14 also has a second flange 16 projecting therefrom which is of 25 less diameter than the flange 15 and is located within the flange 15 and is spaced therefrom so as to provide an annular groove 21. The periphery of these flanges is of 30 similar shape. The lateral edge of each flange is shaped to form cams for taking up 35 and releasing the thread. The member 14 carrying these flanges just referred to has a hub 19 which fits on the end of the shaft 6 and is secured thereto by means of a set screw 20. The threads are led through thread 40 guides 22 and 23 formed in a member 24 carried by a shank 25. This shank has an inwardly bent portion 26 so that the member 24 lies within the cylindrical flanged thread 45 controllers as clearly shown in Figures 3 and 4 of the drawings. Secured to the end of the shaft is a cam plate 17. Said cam plate is fastened to the shaft by means of a screw 18. A pin 19^a carried by the end of the shaft fits within the hole in this cam plate and 50 holds the same from rotating on the shaft. The member 24 is provided with an opening 27 through which the screw 18 can be readily reached. This member 17 has a raised cam portion 17^a which extends 55 throughout about two-thirds of the circumference of said member 17. Said raised portion 17^a is tapered at its edges. The purpose of this raised member is to engage the threads between the thread guides 22 and 23 as the shaft rotates, and press the thread 60 against the member 24. Thus it is that the raised portion acts as a nipper, preventing the take-up from drawing thread from the supply from the time that the loopers begin 65 their retracting movement until the points of the loopers engage the needle loop on the succeeding stitch. The shank 25 is secured to a bracket 28 which is formed as a part of an auxiliary frame 29 secured to the main 70 frame of the machine and extending about

the thread controllers on the end of the shaft 6. A screw 30 passes through an opening 31 in the end of the shank and threaded into this bracket 28. A bolt 32 carried by the auxiliary frame 29 terminates adjacent the 75 shank portion 25 of the member carrying the thread guides. This screw can be shifted endwise on the auxiliary frame and its purpose is to force the shank inwardly or to allow it to yield outwardly and thus vary 80 the nipping pressure of the raised portion 17^a on the thread between the thread guides. From the above it will be noted that I have provided a moving member and a stationary member, neither of which is intended to yield, but which are so positioned as to grip 85 the thread without causing sufficient pressure to break the thread off. When the stationary member is adjusted to increase the grip on the thread, or change the position of the parts for different sizes of threads, the time of gripping is not in any way changed. The time when the thread is gripped is always determined by the shape of the cam portion 17^a on the cam plate 17. No matter 90 95 what the adjustment of the stationary member may be, this cam portion 17^a will always grip the thread at the same time in the cycle of operation of the looper, and release it at the same time; it does not vary. In other words, the length of the thread gripping period for all adjustments is precisely the same, and the time of action of this thread gripping period in the stitch cycle is always 100 the same.

Cooperating with these rotating controllers is a retainer finger 35. Said retainer finger is secured to the auxiliary frame by a locking screw 36. The auxiliary frame is provided with a recess which receives the 105 shank of the support for the retainer finger, and this, together with the screw, serves as a means for rigidly securing the retainer finger in place. This retainer finger extends in between the peripheral shells of the controlling members and runs in the annular grooves 21 therebetween. Said retainer finger is provided with a notch 37 which is always outside of the peripheral cam surface of the thread controllers. It likewise has an inwardly projecting shoulder 38 which extends 110 within the extremely high portions of the thread controllers.

The mode of operation of this retainer finger will be described later. Associated with 120 the retainer finger is a cast off finger 39. Said cast off finger 39 is secured to the bracket 28 by means of a bolt 40. The bracket is formed with a recess in which the shank of the cast off finger seats, and the bolt holds said finger in said recess, and together with the walls of the recess, serve as a means for firmly clamping the finger. The shank of the cast off finger is bent back upon itself, thus forming 125 a U-shaped shank as clearly shown in Fig. 130

2 of the drawings, and the bolt passes through the slot formed by the U-shaped shank and serves to permit the shank of the cast off finger to be adjusted and thus the cast off finger 5 adjusted relative to the controlling members. This cast off finger projects into the annular groove 21 between the shell rims of the inner and outer thread controllers. By adjusting this cast off finger in a direction outwardly 10 away from the controlling cam and longitudinally of the axis of rotation of the same the thread will be cast off at an earlier interval in the cycle of rotation of the controlling cam, and by adjusting the cast off inwardly toward 15 the rotating controlling cam it will cause the thread to be cast off at a later period in the cycle of rotation of the controlling member. It will be noted that this cast off is mounted independently of the retainer 35 and, therefore, 20 the cast off may be adjusted without in any way disturbing the position of the retainer relative to the controlling member. The thread after leaving the thread guides 22 and 23, passes across the edges of the overhanging portions of the controllers, and thence in rear of a thread guide 41 and then along a channel in a plate 42 until it reaches the interior of the work supporting arm. Here it passes in rear of a guiding wire 43, 25 thence along the work supporting arm to suitable guide eyes attached thereto and to the loopers in the usual way. The channel in the plate 42 is covered by means of a spring pressed cover plate 44 (see Figures 2 and 7).

30 Referring to Figures 8 to 10 inclusive, I have shown more or less diagrammatically the thread controllers and the loopers as they are related to each other during the operation of the machine. In Fig. 8 of the drawings, the 35 looper has moved forward to the end of its stroke and is about to be retracted. The controllers rotate in the direction of the arrow in this figure. When the threads pass from the hill or raised portion *a* to the depression or 40 valley *b*, thread is given up to the loopers, and this permits the loopers to move forward to the ends of their strokes without straining the thread to a breaking point. In Fig. 45 9, the loopers are on their rearward movement, and as they move back, they also move sidewise and form a thread triangle for the needles to enter. It is essential that the threads should be put under tension in forming the thread triangle and this is accomplished by the raised or hill portion of the thread controller. The cast off finger 39 resists the 50 tendency of the projecting cam *d* to carry the thread around with the rotating controller and thus insures that the thread will follow 55 or ride along the peripheral edge of the controller. The thread can not slip over the shoulder *d* of the thread controller and become slack by reason of the fact that the check finger 35 comes into play and holds the 60 thread until after the raised cam portion of 65

the controller has passed the thread, after which the thread is gradually given up by the recessed portion *e* of the thread controller. This enables the loopers to move to the rear ends of their strokes under a substantially 70 taut thread and aid in the setting of the stitch. In Fig. 10, the loopers are shown at the rear ends of their stroke. As the loopers move forward, the raised portion *g* comes into play to take up the threads in a manner similar 75 to that described in connection with the shoulered part *c* and thus it is that the looper threads are taken up on the forward movement of the loopers and all liability of the threads buckling and causing skipping of 80 stitches is prevented.

It will be understood, of course, that the two thread controlling flanges are similar in construction, although one within the other. The two looper threads passing across 85 the controlling cam surfaces are crowded in a direction lengthwise of the shaft carrying the rotating cam flanges and consequently there is no tendency of the threads to roll one on the other. Furthermore, if a thread 90 should break, the end of the thread cannot wind up in the shaft as usually occurs in connection with rotary take-ups and controllers, for the reason that the cam members overhang the end of the shaft, and there is 95 no chance for the end of the thread to be caught by any rotating part on the shaft. Then again, the thread controlling cams are readily accessible and may be easily adjusted 100 on the supporting shaft therefor by loosening the set screws and turning the hub of the members carrying the projecting cams. The cast off finger is likewise very accessible for adjustment. The auxiliary frame is provided 105 with a cover or lid 45 for covering over the parts of the thread controller.

While I have described my improved thread controller as used in connection with two looper threads and it has special advantages with two threads, nevertheless it may 110 be equally as well used with a single looper thread, or with more than two threads.

While I have also described my improved thread controller as used in connection with a side wheel machine and on the end of a rotating shaft, it will be understood that it can 115 be used in connection with other types of machines, and otherwise disposed in the machine.

It is obvious that minor changes in the details of construction and the arrangement of the parts may be made without departing from the spirit of the invention as set forth in the appended claims.

Having thus described the invention, what 120 I claim as new and desire to secure by Letters Patent, is—

1. A thread controller for the looper thread of a sewing machine comprising a rotating shaft, a cylindrical flange mounted on and 125

overhanging the end of said shaft, the edge of said flange having a laterally projecting thread engaging cam, and means located radially within and without said flange for 5 directing the looper thread into the path of said thread cam at one portion of the path of travel thereof.

2. A thread controller for the looper thread of a sewing machine comprising a rotating 10 shaft, a cylindrical flange mounted on and overhanging the end of said shaft, the edge of said flange having a laterally projecting thread engaging cam, means for directing the looper thread into the path of said thread 15 cam, and a retainer finger cooperating with said cam for temporarily retaining the looper thread shifted into engagement therewith by said cam.

3. A thread controller for the looper thread 20 of a sewing machine comprising a rotating shaft, a cylindrical flange mounted on and overhanging the end of said shaft, the edge of said flange having a laterally projecting thread engaging cam, means for directing the 25 looper thread into the path of said thread cam, and a cast off finger cooperating with said flange for insuring that the looper thread is engaged by said cam projection.

4. A thread controller for the looper thread 30 of a sewing machine comprising a rotating shaft, a cylindrical flange mounted on and overhanging the end of said shaft, the edge of said flange having a laterally projecting thread engaging cam, means for directing 35 the looper thread into the path of said thread cam, a cast off finger for insuring that the looper thread is engaged by the cam, and a retainer finger cooperating with said cam for temporarily retaining the looper thread shifted 40 into engagement therewith by said cam.

5. A thread controller for the looper thread of a sewing machine comprising a rotating shaft, inner and outer cylindrical flanges mounted on and overhanging the end of said 45 shaft, said flanges being spaced from each other so as to form an annular recess therebetween, each flange having similar shaped and disposed projecting thread engaging cams, and means for directing the looper 50 thread into the path of said cams.

6. A thread controller for the looper thread of a sewing machine comprising a rotating shaft, inner and outer cylindrical flanges mounted on and overhanging the end of said 55 shaft, said flanges being spaced from each other so as to form an annular recess therebetween, each flange having similar shaped and disposed projecting thread engaging cams, means for directing the looper thread 60 into the path of said cams, and a retainer finger extending into the annular recess between the cylindrical flanges and cooperating with said cams for temporarily retaining the looper thread shifted into engagement there- 65 with by said cams.

7. A thread controller for the looper thread of a sewing machine comprising a rotating shaft, inner and outer cylindrical flanges mounted on and overhanging the end of said shaft, said flanges being spaced from each other so as to form an annular recess therebetween, each flange having similar shaped and disposed projecting thread engaging cams, means for directing the looper thread into the path of said cams, a retainer finger extending 75 into the annular recess between the cylindrical flanges and cooperating with said cams for temporarily retaining the looper thread shifted into engagement therewith by said cams, and a cast off finger projecting into said 80 annular recess and operating to insure that the thread is lifted over the thread projecting cams.

8. A thread controller for the looper thread of a sewing machine comprising a rotating 85 shaft, cylindrical flanges located one within the other and spaced from each other to form an annular recess, the outer flange being mounted on the end of the rotating shaft and overhanging the same, the inner flange being 90 located within the outer flange and rotating with said shaft, a stationary thread guiding member located within the inner flange and having a thread guide for guiding and holding the thread in engagement with the edges 95 of said thread controlling flanges, said thread controlling flanges having projecting cams for engaging and taking up the looper thread.

9. A thread controller for the looper thread 100 of a sewing machine comprising a rotating shaft, cylindrical flanges located one within the other and spaced from each other to form an annular recess, the outer flange being mounted on the end of the rotating shaft and overhanging the same, the inner flange being 105 located within the outer flange and rotating with said shaft, a stationary thread guiding member located within the inner flange and having a thread guide for guiding and holding the thread in engagement with the edges 110 of said thread controlling flanges, said thread controlling flanges having projecting cams for engaging and taking up the looper thread, said projecting cams being shaped and dis- 115 posed so as to take up the looper thread as the looper moves forward into the needle thread loop, give up looper thread after the looper point is well into said needle thread loop, take up thread on the rearward movement of the 120 looper, give up thread after the needle has entered the looper thread triangle, and take up thread as the looper reaches the rear end of its stroke.

10. A thread controller for the looper 125 thread of a sewing machine comprising a rotating shaft, a cylindrical flange mounted on and overhanging the end of the shaft, and guides cooperating with said flange whereby said flange as it rotates will force the thread 130

- in a direction substantially parallel with the axis of rotation of the thread controller member.
11. A thread controller for the looper thread of a sewing machine comprising a rotating shaft, a cylindrical flange mounted on and overhanging the end of said shaft, the edge of said flange having a projecting thread engaging cam, and means for directing the looper thread into the path of said thread cam, and means carried by the rotating shaft for clamping the thread so as to prevent the thread controller from taking thread from the supply. 70
12. The combination with a needle and a thread carrying looper movable into and out of the needle thread loop; of a thread controller including a rotating shaft, a cylindrical member carried thereby, a peripheral flange on said member concentric with the axis of the shaft and overhanging the same, said flange having projecting cam portions for engaging the thread, thread guides for holding the thread in contact with said peripheral flange, a plate carried by the end of the shaft and having a raised portion adapted to nip the thread between the thread guides for preventing the controlling cams from pulling thread from the supply from the time the looper begins its retracting movement until the point of the looper engages the needle loop on the succeeding stitch. 75
13. A thread controller for the looper thread of a sewing machine comprising a rotating shaft, a cylindrical flange mounted on the shaft, and guides cooperating with said flange, said guides being so disposed that the thread makes contact with said flange at one side only of the axis of the shaft, whereby said flange, as it rotates, will force the thread in a direction substantially parallel with the axis of rotation of the thread controller. 80
14. A thread controller for the looper thread of a sewing machine comprising a rotating shaft, a cylindrical flange mounted on the shaft, and guides cooperating with said flange, said guides being so disposed that the thread makes contact with said flange at one side only of the axis of the shaft, whereby said flange, as it rotates, will force the thread in a direction substantially parallel with the axis of rotation of the thread controller, one of said guides being located within the periphery of said cylindrical flange. 85
15. A thread controller for sewing machines comprising a rotating cylindrical flange, the edge of said flange being cam shaped so as to periodically take up and release the thread, and guides located within and without the periphery of said flange adapted to hold the thread in contact with said edge. 90
16. A thread controller for sewing machines comprising a rotating circular member having a laterally projecting cam edge, adapted to engage the thread, and stationary means for holding the thread in engagement with said cam edge at one portion of the path of travel thereof. 95
17. A thread controller for sewing machines, comprising a rotating cylindrical thread engaging member and cooperating guides located within and without the periphery of said member, adapted to guide the thread to be controlled for engagement with the edge of said member. 100
18. A thread controller for sewing machines, comprising a rotating thread engaging member adapted to periodically move the thread in a direction substantially parallel with the axis of rotation, a gripping member rotating with said thread engaging member, and a device cooperating therewith for periodically gripping the thread as it passes from the supply to said thread engaging member. 105
19. A thread take-up for sewing machines comprising a rotating circular member having a projecting cylindrical cam shaped edge, means for holding the thread in engagement with said edge and devices for resisting the tendency of the rotating cams to carry the thread around with the rotating member. 110
20. A thread take-up for sewing machines, comprising a rotating cylindrical flange, the edge of said flange being shaped to periodically take up and release the thread, a member located centrally of said cylindrical flange and rotating therewith, said member being segmental in shape, and a stationary member cooperating with said last-named member for gripping the thread at a point between the thread supply and the point of engagement of said rotating flange. 115
21. A thread controller for sewing machines, comprising a rotating thread engaging member having a cam-shaped edge adapted to periodically move the thread in a direction substantially parallel with the axis of rotation and devices located between the thread supply and the point of engagement with the rotating member for periodically gripping the thread, and means cooperating with said cam shaped edge for causing the thread to be gradually given up. 120
22. A thread controller for sewing machines comprising a rotating cylindrical thread engaging member, the edge of said member being shaped to periodically take up and release the thread, guides adapted to hold the thread in contact with said edge, a member located centrally of said rotating member and segmental in shape, a stationary member disposed relative to said segmental member so as to grip a thread passing between the same intermittently, thereby gripping the thread between the supply and the edge of the thread engaging member, and means for adjusting said stationary member 125

to vary the extent of grip upon the thread, or to adapt said means for threads of different sizes.

23. A thread take-up for sewing machines, comprising a rotating cylindrical flange, the edge of said flange being shaped to periodically take up and release the thread, a member located within said cylindrical flange and concentric with the axis of rotation thereof, 10 said member being segmental in shape and having the forward end thereof inclined, a stationary plate having its end disposed adjacent the face of said rotating segmental member, means for adjusting the position of the 15 end of said plate, said plate having thread guides for guiding the thread between the end of the plate and said rotating member whereby said thread is gripped, said gripping means operating upon the thread between the 20 supply and the flange.

24. A take-up for sewing machines comprising a rotating cylindrical flange having the edge thereof shaped to periodically take up and release the thread, guides located 25 within and without the periphery of said flange for holding said thread in contact with said edge, and means for intermittently gripping and releasing said thread, one of said guides being interposed between said gripping and releasing means and the edge of the 30 rotating flange.

25. A rotatable thread controlling element for sewing machines comprising a cylindrical flange, the edge of said flange having disposed 35 similar laterally projecting cams throughout its periphery, which cams are shaped to periodically take up and give up thread held in contact with the edge of the flange.

26. A take-up for sewing machines comprising a rotating member for taking up and releasing the thread, a member located concentric with said rotating member and rotating therewith, said member being segmental in form, stationary means cooperating with 45 said segmental member for gripping the thread therebetween, and guides for directing the thread from the supply between said gripping members to said rotating take-up member.

50 27. A take-up for sewing machines comprising a rotating member for taking up and releasing the thread, a member located concentric with said rotating member and rotating therewith, said member being segmental in form, stationary means cooperating with 55 said segmental member for gripping the thread therebetween, guides for directing the thread from the supply between said gripping members to said rotating take-up member, said segmental member having the forward end thereof tapered, and means for adjusting said stationary member for varying the gripping action on the thread or positioning said thread gripping members for 60 operation upon threads of different sizes.

28. The combination of a shaft, a thread controlling member mounted on said shaft and having a laterally projecting surface overhanging said shaft, and thread guides located one within and one without the periphery of said thread engaging surface for guiding the thread for engagement therewith, said thread engaging surface being in part cam-shaped and in part straight relative to its path of travel.

70 29. The combination of a shaft, a thread controlling member fixed to said shaft and having a laterally projecting cylindrical flange, thread guides located, one within and one without said flange, said flange being cut away in part to form a take-up, and a cast-off member adapted to cooperate with said flange, said flange and cast-off being shaped so that the thread is moved away from said guides in substantially a circumferential direction of said controlling member.

80 30. A thread controller for sewing machines including in combination a rotating shaft, a thread controller mounted on said shaft and having a laterally projecting thread 90 engaging surface overhanging the axis of the shaft, thread guides located one within and the other without said overhanging portion for directing the thread into the path of said thread engaging surface, a cast off finger 95 adapted to engage said threads and cast the same off from said thread engaging surface, and means for supporting said cast off whereby the same may be adjusted in a direction substantially parallel with the axis of rotation of said shaft for varying the time interval when said thread is cast from the thread 100 engaging surface in the cycle of rotation of said thread controlling member.

105 31. A thread controller for sewing machines including in combination a rotating shaft, a thread controller mounted on said shaft and having a laterally projecting thread engaging surface overhanging the axis of the shaft, thread guides located one within and the other without said overhanging portion for directing the thread into the path of said thread engaging surface, a cast off finger 110 adapted to engage said threads and cast the same off from said thread engaging surface, means for supporting said cast off whereby the same may be adjusted in a direction substantially parallel with the axis of rotation of said shaft for varying the time interval 115 when said thread is cast from the thread engaging surface in the cycle of rotation of said thread controlling member, and a retainer finger mounted independently of said cast off finger and cooperating with said thread engaging surface for temporarily retaining the thread cast from said thread 120 engaging surface.

125 In testimony whereof, I affix my signature.

JAMES R. MOFFATT.
